ALARM DEVICE

John H. V. Finney, Denver, Colo., assignor, by
mesne assignments, to The Dorr Company, Inc.,
New York, N. Y., a corporation of Delaware

Application November 1, 1930. Serial No. 492,749

2 Claims. (Cl. 192—116.5)

This invention relates to overload safety devices and more particularly to devices of this kind which are adapted for use with sedimentation apparatus, such as thickeners of the Dorr 5 type.

In the thickeners to which this invention is particularly applicable, a rotary rake structure acting to transfer the sludge at the bottom of a tank to a central outlet, is mounted on a vertical 10 shaft which is rotated by means of a worm gear mounted thereon and a worm meshing with said worm gear. The moving parts of this apparatus are designed to move only a certain maximum amount of settled solids having a predetermined 15 resistance to the rake mechanism; and it sometimes occurs that due to excessive feed; changes in the character of the solids or changes in the proportion of solids in the feed; or to more than one of these conditions; the settled solids 20 build up to such an extent that the resistance offered to the raking mechanism is above that for which the mechanism was designed and tends to warp and break the mechanism. Such difficulties may also arise from obstruction to the 25 rakes by foreign objects, such as tools, dropped into the tank.

Heretofore such thickeners have been provided with devices responsive to increase of thrust of the worm above a predetermined point 30 to signal the operator that excessive resistance to operation is being experienced by the raking mechanism. It has also been proposed to provide means for automatically throwing off the power under such conditions thereby preventing 35 damage to the raking mechanism. According to the present invention these desired results are effected by means particularly advantageous for producing the same and in addition there is provided a running signal which is effective 40 while the mechanism is not running.

The main object of the invention is to provide improved means for preventing damage under various conditions, to some of which reference has already been made. A further object 45 of the invention relates to the provision of means for indicating that the rake structure is working and which is immediately rendered ineffective for this purpose when the resistance becomes great enough to endanger the rake structure or mechanism.

Other objects and advantages will be apparent upon consideration of the following description and the accompanying drawing in which:—

The figure is a view in front elevation illustrating a preferred embodiment of the inven-

tion, parts being removed or broken away to show the underlying structure.

The objects of the invention are in general attained by providing an alarm or danger signal, a running or safety signal, a device for shutting off the power and means for throwing off said running signal and operating the alarm upon overload or resistance reaching an excessive or dangerous degree and for acting further and shutting off the power upon increase of overload 60 to a still more dangerous degree. In its preferred form the invention is embodied in a construction in which the shaft of a driving worm is yieldably supported against the thrust resulting from operation and serves to move an indicator in accordance with the degree of such thrust or the degree of resistance to the movement of the rake structure. Upon movement of the indicator to a predetermined position a circuit controlling the safety signal is broken and 70 a circuit for operating the alarm is closed, this condition being maintained until the overload is decreased to permit the indicator to move back sufficiently to close the safety signal circuit and open the danger signal circuit, or until this condition is changed in some other way. If, however the overload increases so that the indicator moves past the point at which it throws the danger signal into operation and the running signal out of operation, and reaches a second predetermined point, another circuit is opened and 80 the power is shut off.

Referring to the drawing the worm 10, through which the worm wheel (not shown) connected with the rake structure (not shown) is driven, is 85 rotated in the direction indicated by the arrow 11 and, in driving the worm wheel, is subjected to thrust in the direction of arrow 12. The worm 10 is fixed on a shaft 13 of which the end toward which the thrust acts enters an opening in the 90 worm gear bracket 14, and the thrust is transmitted through a thrust ball bearing 15, mounted on a reduced portion (not shown) of the shaft 13, to a member 16 having a reduced portion entering said opening in the worm gear bracket and engaging said ball bearing and having a broader, plate-like portion mounted on tubular spacers 17 surrounding rods or bolts 18 secured at their inner ends to the worm gear bracket and passing at 95 their outer ends through a head 19 in the form of a plate which is held against the spacers 17 by suitable means such as nuts threaded on said bolts 18. Interposed between the head 19 and the member 16 is a compression or thrust spring 20 of 100 sufficient strength to limit the member 16 to 110

movement within a relatively small range under normal load conditions.

Secured to an upright part of the worm gear bracket 14 is a bracket 23 of which the lower end 5 includes a yoke portion 24 extending horizontally away from the bracket 14 and receiving the lower pivoted end of a pointer 25 mounted to swing in a vertical plane about the axis of a pivot 26 extending across the opening in said yoke portion 24 10 and supported in the side thereof, the pointer being provided at its lower end with a set screw 27 which under normal working conditions is held in engagement with the thrust member 16. This set screw 27 is threaded through the split lower 15 end of the pointer and the pressure on the set screw may be regulated by means, such as a screw or bolt 28.

The means for maintaining the screw 27 in engagement with the member 16 includes an eye bolt 29 connected with the pointer 25 (above the pivot 26) by means of a pivot or pin 30 passing through the eye of the bolt 29 and secured in the pointer. The shank of the bolt 29 passes through an opening in the yoke 24 and the bolt 25 is urged outwardly or away from the pointer, by means of a spring 31 interposed between the yoke 24 and a cup washer 32 held on the shank of the eye bolt by suitable means such as nuts threaded on the end of the shank.

30 Extending upwardly from one side of the yoke 24 is an index bracket 33 having its upper end extended parallel to the path of the upper end of the pointer and in correspondence with the range of movement thereof, and this upper end 35 may be provided along an arcuate part thereof (adjacent to the path of the end of the pointer) with indications representing different load conditions.

The pointer 25 is also utilized to control an 40 overload safety device which, according to the illustrated form, includes a control box 35 in which is slidably mounted a member or rod 36 adjacent to the plane of movement of the pointer and parallel thereto, and provided with stops 37 45 and 38 adjustably secured thereto by suitable means, such as set screws, and located on opposite sides of the pointer. Preferably these stops are so set that when the pointer is in its zero position (for example, when the machine is not 50 running) it will be in engagement with the stop 37 and the member 36 will be at one end of its path of movement, and when the pointer in its movement away from its zero position reaches its middle position it will engage the stop 38. This 55 position of the rod 36 will be maintained during normal operation of the thickener and may therefore be called its normal position.

Mounted in the control box 35 adjacent to the rod 36 is a plate or panel 40 which carries two 60 circuit controlling devices or switches. One of these switches controls two circuits or branch circuits and includes a spring contact arm 41 fixed at one end on a member or block 42 on the panel and arranged to engage a terminal 43 (adjacent 65 to the rod 36) when permitted to do so and to engage a terminal 44 when pressed away from the terminal 43. The fixed end of the contact arm or spring 41 is connected with a conductor 45 in which is connected a suitable source of current, 70 such as a battery 46 and the conductor 45 is connected at the far side from the contact spring 41 with a shunt or branch line 47 containing a running signal, such as a lamp 48, and connected with the terminal 43, and with a shunt or branch line 75 49 containing an overload alarm, such as an elec-

tric bell 50, and connected with the terminal 44. Preferably the spring contact arm 41 is provided with a hump 51 to cooperate with a cam member 52 (of insulating material such as glass or porcelain) mounted on the slideable rod 36 and formed with a low portion 53 to permit the contact part or member at the swinging end of the spring arm 41 to engage the contact or terminal 43 when the rod 36 is in normal position and with a high portion 54 connected with said low portion by means of a short incline so that upon movement of the indicator or pointer 25 to an overload position the hump 51 will ride up the incline to effect engagement of the terminal 44 by the free end of the contact spring and will ride along the high portion to an extent determined by the movement of the pointer.

Upon the opposite side of the rod from the spring contact arm 41 there is provided a spring contact arm 55 fixedly mounted at one end on a block carried by the panel 40 and connected at said block with one end of a power control circuit 56 of which the other end is connected with a terminal 57 carried by the panel in such a position that, when the arm 55 is moved outwardly 100 from the bar 36 to a sufficient extent, it will engage such terminal and close the power control circuit to enable actuation of the shaft 13. Control of spring contact arm 55 may be effected by providing it with a hump 58 which during actuation of the shaft 13 is engaged by a high portion 59 of the cam member 52 to maintain the power control circuit in closed condition, but which upon sufficient movement of the rod 36 by movement of the pointer in an overload indicating 110 direction will ride down an incline to open the power control circuit and rest on a low portion 60 of the cam member. The high and low portions controlling the spring contact arms 41 and 55 are so arranged that upon increase of excessive overload the spring arm 41 will be shifted to throw off the running light 48 and to sound the alarm bell 50 and later, if the overload continues to increase the contact arm 55 will be shifted to open the power control circuit. 115

The operation of the overload safety device in connection with a thickener is substantially as follows: The thickener is started in any suitable manner when the parts are in the positions indicated in the drawing and during normal operation the pointer 25 may remain substantially stationary or may assume different positions between its zero position and its mid-position without producing any effect on the safety device. If, however, the resistance to operation becomes excessive (that is, an overload exists), the pointer 25 will engage the stop 38 and effect shifting of the rod 36 and consequently of the contact spring 41 to open the circuit of the running light or lamp 48 and close the circuit of the alarm or bell 50. 125 The operator may then clear up the difficulty or the difficulty may be remedied without any action on the part of the operator. In either event the pointer would return to its normal range of movement and consequently the alarm would be shut off and the running light again thrown on. 130

If after the throwing off of the lamp and the starting of the alarm bell the overload still increases, the cam member 52 will be moved further so that the hump 58 will ride down the incline at the corresponding end of the high portion 59 and rest on the low portion 60 with its free end out of engagement with the terminal 57, thus breaking the power control circuit and stopping the thickener. Upon relief from such over- 135 140 145 150

load the pointer will return to normal position and by engagement with the stop 37 will restore the other parts to their normal positions.

It should be understood that various changes

5 may be made in the construction and arrangement of parts without departing from the true spirit and scope of the invention.

Having thus described my invention, I claim:—

1. Apparatus of the class described having a 10 drive element, means for thrusting said drive element longitudinally upon encountering abnormal resistance, a motor circuit for driving said drive element, a switch for making and breaking said motor circuit, a reciprocable element unitary with 15 said switch and movable in one direction to open said switch and movable in another direction to close said switch, a pivoted lever operable by change of thrust on said drive element, and a selective connection between said reciprocable

element and said switch for motivating said reciprocable element to open and close said switch during movement of said lever through certain portions of its path.

2. Apparatus of the class described having a 80 drive element, means for thrusting said element longitudinally upon encountering abnormal resistance, a motor circuit for driving said drive element, a switch for making and breaking said motor circuit, a reciprocable rod unitary with 85 said switch and movable in one direction to open said switch and movable in another direction to close said switch, a pivoted pointer operable by change of thrust on said drive element for motivating said rod, and stops on said rod to permit 90 operable connection of said pointer with said rod during movement of said pointer through certain portions of its path.
